SLIDER FOR SEPARABLE FASTENERS

Robert C. Legat, New Britain, Conn., assignor to
The G. E. Prentice Mfg. Co., New Britain,
Conn., a corporation of Connecticut

Application February 20, 1943, Serial No. 476,539

15 Claims. (Cl. 24—205)

This invention relates to sliders for separable fasteners and has for its principal object the provision of a slider which is so constructed that it may be readily assembled on or removed from a fastener structure incorporated in a garment or other structure without the use of tools and at will.

Separable fasteners of the type indicated usually comprise a pair of stringers having rows of interlocking elements attached along the opposed edges thereof and a slider embracing both rows of elements and movable along such rows for interlocking or disengaging the elements. Movement of the slider on the fastener is usually accomplished by manual operation of a finger tab which is pivotally attached to one plate of the slider, usually the outer one. At one end of the stringers and adjacent to the endmost interlocking elements thereon, are usually provided end stops for limiting the movement of the slider in the closing direction. In the opening direction, the movement of the slider is usually limited by a third stop which is positioned adjacent to the interlocking elements at the other end of the stringers and binds both stringers together. These end stops are permanent parts of the fastener structure, usually consisting of metallic members which are securely clinched onto the reinforced opposed edges of the stringers, and in most cases, define the limits of the opening in the garment or structure in which the fastener is incorporated. The slider is thus restricted in its movements on the fastener both in the opening and closing directions. The slider usually comprises a pair of spaced guide plates which are rigidly maintained in a predetermined spaced relation such that the slider cannot go beyond the end stops in either the opening or closing direction. The means in the slider for maintaining this spaced relation of the plates usually include an end member, usually integrally formed with one end of the plates, and a wedge-shaped separating member which may be riveted or otherwise permanently secured intermediate the plates. Thus when a slider is once mounted on a fastener structure and the end stops thereof are affixed in proper position, the slider can no longer be removed therefrom without the use of tools or damage to the slider or to the fastener structure.

Slide fastener structures in use on articles are often subjected to conditions which are so severe that the plates of the slider become distorted or bent away from their normal predetermined spaced relation in a manner either to in-

terfere with the slider's proper control of the fastener elements on the stringers, or to make the slider as an operating member wholly inoperative. In most cases this damage to the slider is such that it cannot be suitably repaired except by a skilled workman or without the use of special tools which are not available to the user. For all practical purposes, therefore, the damaged slider renders the fastener useless and its inoperability may not only cause the article to which it is attached to become entirely unsuitable for its purposes but as a result thereof may cause serious consequences to ensue unless the damage is repaired quickly and this is not often possible under many conditions of use. It is, therefore, the purpose of the present invention to provide a slider which may be quickly and readily substituted for a damaged slider on a fastener structure without the use of any tools or special equipment in order that the article to which the fastener is attached may continue to be utilized for the purposes for which it was designed.

In accordance with the present invention, the two guide plates of the slider are so constructed and arranged that one may be moved relative to the other to enable the slider to be positioned in proper relation with respect to the interlocking elements on the stringers of a fastener which is incorporated in an article and intermediate the end stops thereof. Associated with the two relatively movable plates are means for maintaining them in proper spaced relation for operation of the fastener and for enabling the slider to be readily disengaged from the interlocking elements when it is desired to separate it from the fastener.

The advantages of this construction, as well as the novel details of construction thereof, will more readily appear during the course of the following specification when read in connection with the accompanying drawings, in which Fig. 1 is a top plan view of a portion of an article having a fastener carrying a slider embodying the novel features of this invention; Fig. 2 is a right-hand side view of the fastener parts shown in Fig. 1 with the upper portion of the right-hand stringer omitted for the sake of clearness; Fig. 3 is a left-hand side view of the slider shown in Fig. 1; Fig. 4 is a bottom plan view of the slider shown in Fig. 1; Fig. 5 is a view similar to Fig. 3 but showing the manner in which the two guide plates may be separated for assembling the slider on or removing it from the fastener structure; Fig. 6 is a side view of another embodiment of

the invention and illustrating the positions of the parts in this embodiment when the guide plates are in separated condition; Fig. 7 is a view similar to Fig. 6 but showing the guide plates clamped in closed position; Fig. 8 is a top plan view of the slider shown in Figs. 6 and 7; Fig. 9 is a bottom plan view of this modified slider; Fig. 10 is a front view of the modified slider; Fig. 11 is a side view of a still further modified form of the invention, the parts thereof being adjusted to enable the slider to be positioned on or removed from the fastener structure; Fig. 12 is a view similar to Fig. 11 and partly in section, showing the arrangement of the parts in proper operating condition; Fig. 13 is a top plan view of the modified slider shown in Figs. 11 and 12, and Fig. 14 is a sectional view of the third embodiment taken along the lines 14—14 of Fig. 12.

In the preferred embodiment of the invention illustrated in Figs. 1 to 5 of the drawings, the reference characters 10 and 11 designate the stringers of the fastener structure which are usually constituted of fabric and stitched to the material of the article forming the side edges of the opening in the article to be closed by the fastener structure. The stringers 10 and 11 are reenforced along their opposed edges to provide a satisfactory gripping medium for the rows of interlocking elements 12 and 13 clamped to such edges. As is customary, the elements of each row are staggered with relation to the elements in the other row so that the elements of both rows may be successively brought together and progressively interlocked by means of a slider which is generally indicated by the reference numeral 14. Also clamped to the opposed reenforced edges of both stringers 10 and 11 in the region immediately below the lowermost interlocking element in the rows and positioned closely adjacent to the latter, is an end stop 15 for limiting the movement of the slider 14 in the opening direction. Clamped to the stringers 10 and 11 adjacent the uppermost interlocking elements in the rows thereof, are end stops 16, 16 which limit the travel of the slider in the closing direction. Thus the stops 15 and 16 define the range of movement of the slider on the fastener and in the ordinary fastener maintain the slider in permanent association with the stringers and interlocking elements.

The slider 14 comprises a pair of top and bottom wings or plates 17 and 18 which are similarly formed and the lateral edges of which are bent inwardly to provide the side guide flanges 19 and 20, respectively. Also formed integrally with the upper ends of the plates 17 and 18 are two inwardly projecting members 21 and 22, respectively. The two plates 17 and 18 are secured to the inner faces of a pair of jaws 23 and 24, respectively, so that the flanges 19 and member 21 of the plate 17 extend in opposed relation to the flanges 20 and member 22 of the plate 18. The inner surface of the jaw 23 is provided with a recess through which extends a portion of the pull tab 24 which is grasped by the user to manually move the slider 14 longitudinally of the fastener along the rows of elements. The jaw 23 forms part of a base plate 26 positioned above the slider plates 17 and 18 and extending transversely thereto, while the jaw 24 forms part of a base plate 27 positioned similarly above the slider plates 17 and 18. The two plates 26 and 27 are offset with relation to their respective jaws, as is shown in Figs. 1 and 4 of the drawings, so that the inner engaging surfaces thereof extend sub-

stantially through the longitudinal central axis of the slider and such plates are positioned adjacently above the inwardly projecting members 21 and 22 of the slider plates. The plates 26 and 27 are provided with aligned apertures extending through the longitudinal central axis of the slider and through which apertures extends a tubular rivet 28 which connects the two plates together in pivotal relation. Thus the two jaws 23 and 24 and consequently the slider plates 17 and 18 are movable relative to each other about the rivet 28 as a pivot. The lengths of the projecting members 21 and 22 are such that their free ends do not engage to prevent the flanges 19 and 20 from coming into contact with one another, although it is within the contemplation of the invention to make the lengths of such members 21 and 22 such that they function as stops to restrict movement of the plates towards each other, as in the embodiment illustrated in Figs. 11 to 14 of the drawings, such restriction being predetermined and depending upon the sizes of the elements in the fastener structures on which the slider may be used. The projecting members limit movement of the plates 17 and 18 away from each other by engaging with the lower transverse edges of the base plates 26 and 27.

The upper end of the plate 27 above the rivet 28 is cut away to form a cam surface 29 (see Figs. 3 and 5) adapted to be engaged by a cam member 30 having a finger portion 31 and an offset portion 32 which extends first at right angles to the member 30 and through an aperture in the plate 26 and then in substantial parallelism to such member 30 to terminate at a point substantially flush with the camming face of the member 30. The space between the outer end of the offset portion 32 and the member 30 is slightly less than the thickness of the plate 26 in the region thereof traversed by the cam member 30 so that when such plate is between such member it is necessary to apply positive manual force to the finger piece 31 to move the cam member 30 from one position to another and when such member finger piece is released, the member 30 will remain in position until positively removed therefrom. It will be noted also that the offset portion 32 is so formed with respect to the cam member 30 that when the latter is in engagement with the cam surface 29, any forces tending to separate the slider plates 17 and 18 will be transmitted in a straight line to such offset portion and will not tend to cause rotation of such member about the offset portion 32 as a pivot.

It will be understood from the foregoing, that when the cam member 30 is pivoted away from the cam surface 29, as is illustrated in Fig. 5 of the drawings, the slider plates 17 and 18 can be moved apart to their fullest extent, that is, with the projecting members 21 and 22 in engagement with the lower transverse surfaces of the jaw base plates 26 and 27. The slider can then be readily inserted on the fastener structure intermediate the stops 15 and 16 in such manner that the lower narrowed portions of the plates 17 and 18 overlie a plurality of interlocked elements if the fastener structure is only partially opened or abut against the bottom stop 15 if the fastener structure is fully opened. The side guide flanges 19, 19 of the slider plate 17 and the guide flanges 20, 20 of the slider plate 18 are spaced apart a predetermined distance to enable the slider to accommodate fastener elements of varying sizes. Preferably also the lower ends of the flanges 19 and 20 flare outwardly as is illustrated in the

drawings to enable the slider to be assembled at any point on the fastener even though the latter is entirely opened, as with such formation of the flanges the mounted slider can be moved in the opening direction over the unopened portions of the slider and on movement in the opposite or closing direction will operate to interlock the fastener elements. When the opened or spread plates are properly positioned on the fastener elements, the cam member 30 is actuated by operation of the finger piece 31 to engage the cam surface 29 and is moved on such surface until the plates 17 and 18 have been closed to a position where the slider can be actuated properly by means of the pull tab 25. Should it be desired to lock the slider in any position on the fastener structure while in use, this can be accomplished by further moving or advancing the cam member 30 with respect to the cam surface 29 until the slider plates 17 and 18 are securely clamped on the fastener elements. When it is desired to again actuate the slider the cam member 30 is retracted an amount sufficient to enable ready actuation through the pull tab 25. When it is desired to remove the slider from the fastener structure, this can be readily accomplished by retracting the cam member 30 until it is disengaged from the cam surface 29 thereby releasing the jaws 23 and 24 and enabling the slider plates 17 and 18 to be spread apart.

In the embodiment illustrated in Figs. 6 to 10 of the drawings, the slider plates 17' and 18' are slidably connected together, for movement toward and away from each other, by means which include an inwardly extending member or portion 35 integral with the upper end of the slider plate 17' and having a reduced portion 36 which extends through an aperture provided in a prolonged portion 37 of the slider plate 18'. The outer end of the portion 36 is turned and slightly flattened to permanently lock the portions 36 and 37 together. Secured in any suitable manner to the plate 18' is a separating member 38 which is wedge-shaped intermediate the plates 17' and 18' and which extends loosely through an aperture provided in the slider plate 17'. The outer end of the member 38 is enlarged to limit the spread of the slider plate 17' with respect to the slider plate 18'. Pivoted mounted on the enlarged end of the member 38 is a pull tab 25' and a cam member 39 whose cam surface 40 is adapted to engage the exterior surface of the slider plate 17' when such member is pivoted toward plate 17' and to force such plate toward the plate 18'.

It will be observed from the foregoing, that in this modified construction, the plate 17' is readily movable toward or away from the plate 18' when the cam member 39 is in the position indicated in Fig. 6 of the drawings, such movement being confined in one direction by the elongated portion 37 engaging with the shoulders formed between the member 35 and its reduced portion 36 and being confined in the other direction by the deformed outer end of such portion 36 and the enlarged end portion of the separating member 38. When the slider is properly mounted on the interlocking elements of a fastener structure, the cam member 39 is pivoted toward the slider plate 17' to enable its cam surface 40 to engage the exterior surface of such plate and force the plate 17' toward the plate 18'. When cam member 39 has been moved to the position shown in Fig. 7 of the drawings, with the high point of its cam surface 40 moved past its pivotal point on the enlarged portion of mem-

ber 38, the slider plates 17' and 18' will be in proper relation for locking or disengaging the elements of the fastener structure. In this position of the cam member 39, it cannot be moved outwardly to release the plates 17' and 18' by any forces tending to spread such plates in the use of the slider, as the high point in the cam surface 40 is offset with respect to the pivotal connection of such member with the separating member 38 and accordingly, any forces so acting on the plates 17' and 18' will only tend to further lock the cam member 39 in position.

In the embodiment illustrated in Figs. 11 to 14 of the drawings, the purposes of the invention are accomplished by slidably mounting the slider plate 17'' on a separating member 45 secured at one end in any suitable manner to the slider plate 18'' and extending loosely through an aperture provided in the slider plate 17''. The portion of member 45 intermediate the slider plates is substantially wedge-shaped to enable it to function as a separating member in the operation of the slider. The remaining portion of such member 45, that is, that portion thereof which projects from the slider plate 17'' when the in-turned portions 21' and 22' of the plates 17'' and 18'', respectively, are in abutting engagement, is provided on two opposite surfaces with portions of screw threads which are in threaded engagement with a female screw thread provided on the member or plate 46 disposed in parallelism with the slider plates. The outer end of member 45 is spread to maintain the plate 46 and slider plate 17'' assembled thereon. On either side of the threaded aperture of the plate 46, such plate is provided with an outwardly projecting ear 47 which serve as bearings to pivotally support the pull tab 25''. Beyond the ears 47, 47, the material of the plate 46 is struck down to provide a locking projection 48 adapted to engage with a locking recess or aperture 49 provided in the plate 17''. It will thus be seen, that by grasping the finger tab 25'' and screwing the plate 46 down on the thread portions of member 45, the plate 17'' may be moved toward the plate 18'' until the inwardly projecting portions 21' and 22' of such plates engage in abutting relation. The plates 17'' and 18'' of the slider will then be in proper spaced relation for interlocking or disengaging the elements of the fastener structure. The parts are so constructed that when the portions 21' and 22' are engaged, the locking projection 48 will engage with the aperture 49 in the slider plate 17'' to lock the plate 46 in position until positively disengaged from such locked relation with the plate 17''.

It will appear from the foregoing, that this invention provides a novel separating or detachable slider which can be attached readily to or removed from a fastener structure incorporated in an article, or more broadly speaking, in a fastener structure so constructed and/or arranged that a slider of usual construction cannot be separated therefrom unless some element is disassembled. As the attachment or removal of the slider does not require the use of any tools and can be accomplished by any user, it has special advantage as a repair slider to be substituted for the regular slider of a fastener structure which has become damaged or rendered inoperative, until the latter can be repaired or a new slider of usual construction incorporated in the fastener. While I have illustrated and described several forms which the invention may assume in practice, it will be understood that various other forms

and/or modifications may be devised which do not depart from the spirit of my invention or the scope of the appended claims.

I claim:

1. A slider for a separable fastener of the type which includes a pair of stringers provided with interlocking fastener means along their opposed edges, comprising a pair of plates adapted to receive therebetween the interlocking means of a fastener, means supporting said plates and constructed and arranged to permit movement of such plates relative to one another to vary the space therebetween, and manually operable means mounted on said supporting means for limiting the range of movement of said plates relative to each other.

2. A slider for a separable fastener of the type which includes a pair of stringers provided with interlocking fastener means along their opposed edges, comprising a pair of plates adapted to receive therebetween the interlocking means of a fastener, means supporting said plates and constructed and arranged to permit movement of said plates relative to each other to vary the space therebetween and within fixed predetermined limits, and means connected to said supporting means for restricting the range of movement of said plates relative to each other to a range less than the range defined by said fixed limits, said last mentioned means being manually operable.

3. A slider for a separable fastener of the type which includes a pair of stringers provided with interlocking fastener means along their opposed edges, comprising a pair of plates adapted to receive therebetween the interlocking means of a fastener, means supporting said plates for movement relative to each other to vary the space therebetween, means on said supporting means permanently fixing the range of movement of said plates away from each other, and manually operable means mounted on said supporting means for temporarily restricting the range of movement of said plates relative to each other to a range less than said permanent range.

4. A slider for a separable fastener of the type which includes a pair of stringers provided with interlocking fastener means along their opposed edges, comprising a pair of plates adapted to receive therebetween the interlocking means of a fastener, means supporting said plates for movement relative to each other to vary the space therebetween, means on said supporting means for limiting the range of movement of said plates away from each other and adjustable means mounted on said supporting means for restricting the movements of said plates away from each other to a range less than said first mentioned range, said last mentioned means being manually operable.

5. A slider for a separable fastener of the type which includes a pair of stringers provided with interlocking fastener means along their opposed edges, comprising a pair of plates adapted to receive therebetween the interlocking means of a fastener, means supporting said plates for movement relative to each other to vary the space therebetween, a movable cam engaging surface fixed with relation to one of said plates and arranged so that pressure thereon will cause movement of such plate towards the other plate and a camming member mounted on said supporting means and constructed and arranged to cooperate with said surface, said member being manually operable in one direction to bear on said

surface so as to move said plates from a spread condition into closer spaced relation.

6. A slider for a separable fastener of the type which includes a pair of stringers provided with interlocking fastener means along their opposed edges, comprising a pair of plates adapted to receive therebetween the interlocking means of a fastener, means supporting said plates for movement relative to each other to vary the space therebetween, cooperative camming members operable to move said plates from a spread condition into closer spaced relation, one of said members being fixed with relation to one of said plates and the other being mounted on said supporting means for movement relative to such plate, and said camming members being constructed and arranged to maintain said plates in such closer relation against forces tending to spread the plates apart.

7. A slider for a separable fastener of the type which includes a pair of stringers provided with interlocking fastener means along their opposed edges, comprising a pair of plates adapted to receive therebetween the interlocking means of a fastener, means supporting said plates for movement relative to each other to vary the space therebetween, a movable cam engaging surface fixed with relation to one of said plates and arranged so that pressure thereon will cause movement of such plate towards the other plate, and a camming member manually movable about a fixed axis, said member being mounted on said supporting means and adapted to cooperate with said surface when operated in one direction to move said plates from a spread condition into closer spaced relation, said surface and camming member being constructed and arranged to maintain said plates in such closer relation against forces tending to spread the plates apart and to maintain said plates clamped against the interlocking means of the fastener to prevent movement of the slider longitudinally of the separable fastener.

8. A slider for a separable fastener of the type which includes a pair of stringers provided with interlocking fastener means along their opposed edges, comprising a pair of plates adapted to receive therebetween the interlocking means of a fastener, means supporting said plates for movement relative to each other to vary the space therebetween, means for limiting the movement of said plates toward each other, means on said supporting means for limiting the movement of said plates away from each other, and adjustable means mounted on said supporting means for restricting the movement of said plates away from each other to a point intermediate the range defined by said limiting means.

9. A slider for a separable fastener of the type which includes a pair of stringers provided with interlocking fastener means along their opposed edges, comprising a pair of plates adapted to receive therebetween the interlocking means of a fastener, a pair of pivotally connected jaws supporting said plates for movement relative each other to vary the space between such plates, a cam engaging surface provided on one of said jaws and a manually movable cam member provided on the other of said jaws and constructed and arranged to coact with said surface to move said plates from a spread condition into closer relation.

10. A slider such as defined in claim 9 in which each of said plates are provided with side guide

flanges extending in opposed relation to the side guide flanges of the other plate and in which the interior surfaces of said plates intermediate their guide flanges are flat and unobstructed.

11. A slider such as defined in claim 9, in which said plates are positioned intermediate said jaws and said jaws have a portion extending transversely of said plates and adapted to coact with an inner portion of said plates to limit the movement of said plates away from each other.

12. A slider such as defined in claim 9 in which said cam member is pivotally connected to one of said jaws for movement about a fixed axis relative to such jaw and includes a finger piece adapted to be grasped by the user, a portion adapted to engage with said cam-engaging surface and a portion adapted to coact with a surface of the jaw to which said member is connected to maintain the engagement of said member with said cam-engaging surface until positively removed therefrom.

13. A slider for a separable fastener of the type which includes a pair of stringers provided with interlocking fastener means along their opposed edges, comprising a pair of plates adapted to receive therebetween the interlocking means of a fastener, means supporting said plates for movement relative to each other to vary the space

therebetween, a separating member attached at one end to one of said plates and extending loosely through the other of said plates to project beyond its exterior surface, means for restricting the range of movement of said other plate on said separating member and adjustable means on the projecting end of said separating means to move said other plate from a spread condition into closer relation with said first-mentioned plate.

14. A slider such as claimed in claim 13 in which said adjustable means comprises a cam member pivotally connected to said separating member and adapted upon movement towards said other plate to engage the exterior surface of the latter and to force said plate into such closer relation.

15. A slider such as claimed in claim 13 in which said adjustable means includes a member threadedly engaged with the projecting end of said separating means and adapted to be screwed down thereon to force said other plate towards said first-mentioned plate, and cooperative locking means provided on said member and said other plate and adapted to interlock to prevent inadvertent movement of said member relative to said other plate.

ROBERT C. LEGAT.
